UNDERFIRED REGENERATIVE COKE OVEN

Walter Stäckel, Bochum, Germany, assignor to
 Otto-Wilputte Ovenbouw Mij. (Otto-Wilputte
 Oven Construction Company) N. V., The
 Hague, Netherlands, a corporation of the
 Netherlands

Application July 7, 1939, Serial No. 283,150
 In Germany November 14, 1938

3 Claims. (Cl. 202—241)

The present invention relates to coke ovens and particularly to horizontal underfired coke ovens having horizontal regenerators extending parallel to the horizontally elongated coking chambers and having horizontal metal distribution pipes each alongside a corresponding regenerator and connected thereto so as to supply to the regenerator at points distributed along its length, a combustible agent to be preheated in the regenerator. The combustible agent so supplied may be a lean fuel gas, or combustion air. In so-called combination ovens, some of the distribution pipes may supply combustion air only, while other distribution pipes may supply either lean gas or combustion air, accordingly as the oven is heated by the combustion of preheated lean fuel gas, or by the combustion of a rich fuel gas which is not preheated.

The object of the present invention is to provide a simple and effective method of, and means for preventing the flow of waste heating gases through such metal distribution pipes, during the periods in which the regenerators respectively associated with the pipes, are serving as "off" regenerators. During each period in which a regenerator is serving as an "off" regenerator, a distribution pipe connected to the regenerator at points distributed along its length provides a bypass or flow path for some of the waste gases flowing through the regenerator to the outlet therefrom then connected to a stack or other exhaustor.

The waste gases ordinarily include sulphur and other constituents which have high dew points, and form condensates which will corrode the metallic distribution pipes if allowed to come in contact therewith. The dew points of some of the constituents forming corrosive condensates are higher than the distribution pipe wall temperatures even when the latter are imbedded in the masonry at the bottom of the battery, and have somewhat higher temperatures than they do when in their more usual location within the subway space beneath the deck or reinforced concrete slab on which the coke oven brick-work is usually carried.

In accordance with the present invention, waste gases are kept out of each of the different distribution pipes during the period in which it is not supplying a combustible agent to the corresponding regenerator for preheating therein, by then passing a non-injurious gaseous fluid, ordinarily air, into the pipe, so as to maintain a slow flow therethrough out of the pipe and into the regenerator through each of the con-

nections to the latter from the pipe. Waste gases may be thus kept out of the pipe by an amount of air or other protective fluid flowing through the pipe, which is not large enough to significantly increase the load on the stack or other means employed to withdraw waste gases from the regenerators.

The various features of novelty which characterize the present invention are pointed out with particularity in the claims annexed to and forming a part of this specification. For a better understanding of the invention, however, its advantages, and specific objects attained by its use, reference should be had to the accompanying drawings and descriptive matter in which I have illustrated and described preferred forms of embodiment of the invention.

Of the drawings:

Fig. 1 is a partial vertical transverse section through a horizontal underfired coke oven of conventional design;

Fig. 2 is a partial section on the line 2—2 of Fig. 1;

Fig. 3 is a partial section through a supply valve associated with a distribution pipe, the section being taken on the line 3—3 of Fig. 1;

Fig. 4 is a section taken similarly to Fig. 1 illustrating a modified form of the invention;

Fig. 5 is a partial section on the line 5—5 of Fig. 4; and

Fig. 6 is a section on the line 6—6 of Fig. 4 through one of the distribution valves shown in Figs. 4 and 5.

In Figs. 1—3 of the drawings, I have illustrated the use of the present invention in an underfired coke oven battery of the most usual type comprising horizontal elongated coking chambers which extend transversely of the battery, and alternate with similarly extending heating walls. The latter are formed with vertical combustion flues 2, each of which is connected at its lower end by separate channels 8 to a regenerator 6 and to a regenerator 7. Each regenerator 7 is used to preheat combustion air, but the regenerators 6 may be used to preheat lean fuel gas. As shown, there are two regenerators 7 between each two adjacent regenerators 6, each of the latter being directly beneath a corresponding coking chamber 1, and connected to flues 2 in each of the two heating walls at opposite sides of said coking chamber. Each regenerator 7 is connected only to flues 2, in a single heating wall.

As those skilled in the art will understand, the regenerator arrangement illustrated in Figs.

1 and 2 is of the character customarily employed in the most usual type of underfired coke ovens, in which the vertical heating flues 2 are connected at their upper end to form so-called 5 twin, or hairpin, flues. With such heating flues, each of the regenerator chambers 6 and 7 may extend from one side of the battery to the other, though, as those skilled in the art will understand, in such ovens, as well as in other known 10 forms of coke ovens with which the invention may be used with advantage, each regenerator may have a length which is a fraction only of the length of the oven chamber, and may be arranged in end to end relation with other regenerators of similar length.

Each of the flues 2 is adapted to serve alternately as an upflow flue, in which fuel gas and combustion air supplied to the lower end of the flue, ignite and burn, during regular periods 20 which alternate with similar periods in which the flue serves as a down flow flue receiving burnt or burning gases from some other flue or flues 2 then serving as upflow flues. The fuel gas supplied to each flue 2 may be a rich fuel 25 gas which does not require preheating, and which, is supplied as shown, through vertical channels 3 in the subjacent regenerator division walls from distribution pipes 4 and 5. The pipes 4 being connected to a set of flues 2, which serve as ignition flues during periods alternating with those in which the remaining flues receive rich 30 fuel gas from the pipes 5 and serves as ignition flues.

Beneath each regenerator 6 is a corresponding sole channel 9, and beneath each regenerator 7, is a corresponding sole channel 10, each regenerator being in free communication all along its length with the corresponding sole channel. The sole channels 9 and 10 are connected by corresponding reversing valves 11 at one side of the battery, or preferably and as shown at each side of the battery, to a corresponding flue or duct 12, which extends longitudinally of the battery, and leads to a chimney or other waste gas exhausting means. Each valve 11 is opened during the periods in which the corresponding regenerator is serving as an "off" regenerator to permit the waste gases then flowing from the flues 2 to and through the regenerator, to pass into the corresponding flue 12. During each period in which a regenerator is serving as an "on" regenerator, each corresponding valve 11 closes communication between the corresponding sole channel, 9 or 10, and the adjacent waste heat flue 12. Each valve 11 is formed with an air-inlet closed by a damper or flap valve 11', which is opened to permit atmospheric air to pass into the corresponding regenerator, when the latter is used in preheating combustion air, but is closed at other times.

In the construction shown in Figs. 1, 2 and 3, each regenerator 6 when used in preheating lean fuel gas is supplied with such gas from a fuel gas supply main 13 through a corresponding valve 14 and metal horizontal distribution pipe 15, and 55 its lateral outlet branches 15'. The main 13 extends longitudinally of the battery adjacent one side of the latter, and each distribution pipe 15 extends transversely of the battery and is located in the upper portion of the subway space, immediately beneath the deck or supporting platform 16 on which the coke oven brickwork is carried. The delivery branches 15' of each pipe 15 extend through openings in the deck 16 and into vertical 60 passages in the bottom wall of the corresponding regenerator sole channel 9 so as to deliver gas to

the latter at a plurality of points distributed along the length of the sole channel. The gas flow through each pipe 15' may be regulated by means of a corresponding obturator or other regulating device 17, which is accessible for regulation through a corresponding opening formed in the underside of the pipe 15 and normally closed by a removable cap or plug member 18.

As shown, each valve 14 comprises a casing in which is mounted a rotatable valve member 14a. The latter is formed with a through passage 14b, which when vertically disposed, passes gas from the supply main 13 to the corresponding distribution pipe 15. When rotated into the position in which the passage 14b is horizontal as shown in Fig. 3, the valve member 14a prevents the outflow of gas from the main 13 through the connection of which the valve forms a part. The valve member 14a may be turned between the position shown in Fig. 3, and that in which the passage 14b is vertical, by a valve operating arm 14', adapted to be periodically oscillated by the usual reversing valve gear (not shown) provided in such a coke oven battery.

For the purposes of the present invention, the 25 casing of the valve 14 is formed with an air inlet port 14'', which, when the valve member is in the position shown in Fig. 3, is in register with one end of the passage 14b. Atmospheric air may be 30 drawn through the inlet 14'' into the passage 14b and thence into the pipe 15 through a small passage or port 14c formed in the upper wall of the valve passage 14b, when the valve member 14a is in the position shown in Fig. 3.

In the normal operation of the apparatus shown in Figs. 1, 2 and 3, when a regenerator 6 is preheating lean gas supplied thereto through the corresponding distribution pipe 15, the two immediately adjacent regenerators 7 are employed in preheating combustion air. The said regenerator 40 6 and the two adjacent regenerators 7, form a regenerator unit which then supplies preheated combustion air and fuel gas to the upburning flues in the two heating walls at opposite sides 45 of the coking chamber 1 directly above the regenerator 6. The other flues 2 in the two heating walls then serve as down flow flues and discharge gases through the corresponding channels 8, each to a regenerator 7 and a regenerator 6 adjacent and at one side of said regenerator unit. 50 During the period in which each regenerator 6 is serving as an "off" regenerator, and has the opposite ends of its sole channel 9 connected through the corresponding valves 11 to the waste heat flues 12, air is drawn into admixture with the waste gases in the sole channel through the outlet branch pipes 15' and pipe 15 and the corresponding valve ports 14'', 14b and 14c. With a 55 suitably small port 14c, enough air may be supplied to the pipe 15 to insure that air will flow upward through each of the branch outlet pipes 15' and thereby prevent heating gases from flowing downward into the pipe 15 through any of the branches 15'.

As those skilled in the art will understand, the 65 general principles of the present invention may be used with advantage in connection with various types of regenerator coke ovens other than that shown in Figs. 1 and 2. For example, they 70 may be used in an oven of the type shown in Figs. 4, 5, and 6, in which the combustible agent preheated in regenerators 6A and 7A extending transversely of the battery, is supplied to the lower portion of each regenerator, at points 75 distributed along its length, through distributed

outlet connections from a corresponding pipe 21 or 22, extending transversely of the battery and imbedded in a masonry layer 20 interposed between the coke oven brickwork proper, and the 5 supporting deck 16 of an underfired battery. As shown, also, the rich fuel distribution pipes 23 are also imbedded in the masonry layer 20.

As shown in Fig. 4, each distribution pipe 21 is connected at one end through a valve 14A to an 10 air main 24 extending longitudinally of the battery, and containing air at a pressure somewhat above that of the atmosphere. The valve 14A, as shown in Fig. 6, is identical in construction with the previously described valve 14, except that 15 in the valve 14A, the air inlet port 14" is omitted, and the valve member 14a is formed with a small port 14d, in alignment with the port 14c. The ports, 14c and 14d collectively provide a suitably restricted passage for the flow of 20 enough air from the main 24 into the distribution pipe 21, to prevent the passage of waste gas into said pipe during the periods in which the corresponding regenerator 7A is serving as an "off" regenerator, and the valve member 14a of the 25 valve 14A is in the position in which the passage of air through the main valve passage 14b is prevented. It is to be noted, however, that in an oven having distribution pipes imbedded in masonry as shown in Figs. 4, 5, and 6, the normal 30 pipe temperatures are higher than those of distribution pipes exposed as shown in Figs. 1 and 2, and in some cases are quite high enough to eliminate serious risk of deformation of corrosive condensates within the pipes.

35 Each distribution pipe 22 and 23 supplying combustible agent to a regenerator 6A is also connected at one end to the air main 24, through valves 14B and 14C. The valve 14C may be a simple valve adjustable between one position in 40 which it closes communication between the main 24 and the distribution pipe 23 and a second or open position in which it does not obstruct communication between the main and distribution pipe. The valve 14B may be identical in construction with the valve 14A, and when the regenerators are all used in preheating combustion air, each valve 14B as well as each valve 14A may be operated by the usual battery reversing gear, to pass air from the main 24 to each of the 45 distribution pipes 21 and 22 during each period in which the corresponding regenerator is an "on" regenerator, and during the alternate "off" periods, the said valve 14A or 14B is adjusted into the position in which air passes at a suitably restricted rate from the main 24 to the corresponding distribution pipe, through the small ports 14c and 14d. When a regenerator 6A is thus used in preheating air, the corresponding valve 14C may be continuously open, but when a regenerator 6A is used in preheating lean gas, its valve 14C is connected to the battery reversing gear, for adjustment to permit or prevent air flow from the main 24 to the regenerator, according 50 ly as the latter is serving as an "on," or as an "off" regenerator.

When a regenerator 6A is used to preheat lean fuel gas, the latter is supplied to the regenerator during its "on" periods of operation, from a lean gas supply main 25 extending longitudinally of 55 the battery at the opposite side of the latter from the main 24. The main 25 is connected to the adjacent end of each distribution pipe 22 through a corresponding valve 26. When lean gas is being preheated and burned each valve 26 60 is connected to the battery reversing gear for

adjustment into its open and back into its closed position at the beginning and end, respectively, of each reversal period in which the corresponding regenerator is an "on" regenerator. When a regenerator 6A is used in preheating combustion air, the corresponding valve 14C may be maintained continuously in its closed position, and to this end may then be disconnected from the battery reversing gear.

The rich gas distribution pipe 23 shown in 10 Figs. 4 and 5 is adapted to receive rich fuel gas from a supply main 27 extending longitudinally of the battery, during the reversal periods in which the corresponding reversing valve 28 is open. During the reversal periods in which the 15 valve 28 is closed, the other end of the pipe 23 may be connected to the air distribution main 24 by adjustment of a corresponding valve 14C so that the distribution pipe 27 may then receive 20 decarbonizing air to burn out graphite deposits in the oven brickwork passages through which rich fuel gas is supplied to the combustion flues.

The outlet connections distributed along the length of the pipe 21, are formed by vertical 25 pipes 30, each welded to the pipe 21 at the margin of registering openings in the walls of the two pipes and through which the two pipes are in free communication. As shown, each pipe 30 has its upper end extending into a channel 31 formed in the coke oven brickwork and opening 30 laterally into the corresponding regenerator 7A, immediately above the top of the corresponding sole channel 10A. As shown, the regenerator space is separated from the sole channel by a 35 perforated member 32, which may be formed of ceramic material.

The outflow from the pipe 21 into, and upward through each pipe 30, is regulated by an obturator 17, shown as comprising a globular upper end portion centrally disposed in and 40 throttling the portion of the pipe 30 above its connection to the pipe 21. The obturator 17 has a rod-like body portion extending down through the pipe 30 and supported on a cap member 18 normally closing the lower end of 45 the pipe. The lower end of the pipe 30 and the cap 18 are below the underside of the supporting deck 16. By replacing each obturator 17 by another including a globular portion of different size the flow capacity of the corresponding outlet 50 connection 30, may be suitably regulated.

Each distribution pipe 22 is adapted to deliver air or combustion gas to the corresponding regenerator 6A through connections including 55 pipes 30 and passages 31 arranged and adjustable as are the connections to the regenerator 7A from the pipe 21. As shown, also, the rich gas distribution pipe 23 is provided with outlet connections comprising vertical pipes 33 connected to the distribution pipe 23, as the pipes 30 are 60 connected to the distribution pipes 21 and 22. Each of the pipes 33 includes an obturator 17, and has its upper end extending into a brickwork passage leading upward to the corresponding combustion flue 2. In the arrangement shown 65 in Figs. 4 and 5, each of the supply passages 31 opens to a corresponding one of a series of regenerator chambers into which the corresponding regenerator 6A or 7A is divided by vertical partitions 34.

The reversing valve 11A through which the regenerator sole channels 10A are connected to the stack, may be like the reversing valves 11 though none of them need include a damper controlled air inlet.

Except for the provisions shown for passing air into each of the distribution pipes 21 and 22 during the periods in which the corresponding regenerator is serving as an off regenerator, the 5 special features of construction and arrangement shown in Figs. 4 and 5 form no part of the present invention, but have been shown and described for the purpose of illustrating the adaptability of the invention claimed herein for 10 use in coke ovens of various types.

While in accordance with the provisions of the statutes, I have illustrated and described the best forms of embodiment of my invention now known to me, it will be apparent to those skilled 15 in the art that changes may be made in the form of the apparatus disclosed without departing from the spirit of my invention as set forth in the appended claims and that in some cases certain features of my invention may be used 20 to advantage without a corresponding use of other features.

Having now described my invention, what I claim as new and desire to secure by Letters Patent, is:

25 1. In the operation of an underfired regenerative coke oven including an elongated regenerator and in which a combustible agent to be preheated in each such regenerator is supplied thereto through a metal pipe alongside the regenerator and having outlets connected to the latter at points distributed along its length and

including means for withdrawing waste gases from said regenerator at its end, the method of excluding waste gases from said metal pipe during periods in which waste gas is being withdrawn from the regenerator, which consists in 5 then passing a non-injurious gas through said pipe and its outlets into the regenerator.

2. An underfired regenerative coke oven battery, comprising in combination an elongated regenerator extending transversely of the battery, means for withdrawing waste gas from the regenerator at its end, means for supplying a combustible agent to be preheated to said regenerator comprising a metallic distribution pipe alongside the regenerator and outlet connections 10 from said pipe to the regenerator distributed transversely of the battery and means for passing a non-injurious gas into said regenerator through said pipe and outlet connections during periods in which waste gases are being withdrawn from the regenerator by the first mentioned means whereby the passage of the waste gases into the distribution pipe is prevented. 15

3. A coke oven battery as specified in claim 1, in which the means for passing a non-injurious 20 gas through the regenerator into the distribution pipe comprises a valve connected to said pipe and through which when opened air may be drawn from the atmosphere by the first mentioned means.

30 WALTER STÄCKEL.
